United States Patent Office

Des. 219,323
Patented Nov. 24, 1970

219,323

BASIN

Lewis F. Bost, Chicago, Ill., assignor to American Hospital Supply Corporation, Evanston, Ill., a corporation of Illinois

Filed July 23, 1969, Ser. No. 18,358

Term of patent 14 years

Int. Cl. D24—99

U.S. Cl. D83—1

FIG. 1

FIG. 2

FIG. 3

FIG. 4

FIG. 5

FIG. 6

FIG. 1 is a perspective view of a basin embodying my design;

FIG. 2 is a top plan view;

FIG. 3 is an elevational view of the front of the basin;

FIG. 4 is an elevational view of the rear of the basin;

FIG. 5 is an elevational view of one end of the basin;

FIG. 6 is a view of the basin's opposite end.

I claim:

The ornamental design for a basin, substantially as shown and described.
